UNITED STATES PATENT OFFICE

LANCELOT WILLIAM WILD, OF LONDON, ENGLAND, ASSIGNOR TO WILD-BARFIELD ELECTRIC FURNACES LIMITED, OF LONDON, ENGLAND

OVEN, FURNACE, OR LIKE STRUCTURE

Application filed April 18, 1930, Serial No. 445,262, and in Great Britain June 11, 1929.

This invention relates to ovens, furnaces, or like heaters, adapted for use in carrying out industrial processes, such as carbonizing, hardening, tempering, or other heat treatments which are carried out in high temperature furnaces.

In such furnaces the air is circulated to a certain extent by convection. In order to increase the circulation of the air, propellor fans or fans having inclined blades have been utilized but have not been entirely successful, due to the action of the pitched blade.

This invention has for its salient object to provide air circulating means for a furnace or oven of the character specified, so constructed and arranged as to supplement the normal current of air produced by convection and to increase the efficiency of operation of the furnace and cut down the time required for heat treatment.

Further objects of the invention will appear from the following specification taken in connection with the drawings, which form a part of this application, and in which

Fig. 1 is a sectional elevation of a furnace having air circulating means constructed in accordance with the invention;

Fig. 2 is a transverse sectional elevation taken substantially on line 2-2 of Fig. 1; and

Fig. 3 is a view similar to Fig. 1 but showing the fan at the top of the heating chamber instead of at the bottom thereof.

The invention briefly described consists of a furnace comprising a heating chamber having suitable heating means therein and a "paddle" fan or a fan having plane blades disposed in the chamber and adapted to cause the air to circulate in a manner to supplement the normal current produced by convection. The blades are preferably arranged radially of the axis of rotation of the fan.

Further details of the invention will appear from the following description.

In the particular embodiment of the invention illustrated in the drawings, there is shown an electric oven adapted particularly for tempering steel. It should be understood, however, that the invention is broadly applicable to other types and forms of ovens

and may be used in ovens which are heated by gas, oil, or by solid fuel.

The oven 10 illustrated in the drawings is preferably made of sheet iron and is lagged with the usual lagging material 12 having poor heat conductivity. The furnace is charged through the top, the top being normally closed by a cover or lid 13, which is also lagged.

The furnace is provided with heaters 14 which are mounted in the corners and extend vertically in the heating chamber of the furnace. A basket 15 is supported by legs 16 which hold the basket in a position vertically spaced from the floor of the furnace.

The air circulating means consists of a paddle type fan having radially disposed plane fan blades 17 which are mounted on the vertical fan shaft 18. The fan is disposed in the space between the bottom of the work support or basket 15 and the floor of the furnace and the shaft 18 extends downwardly through a suitable bearing or bushing 19. A motor 20 drives the shaft 18 and is supported in a bracket 21 which extends below the bottom of the furnace.

The basket or work support 15 is preferably perforated in its side wall, as shown at 22, and in its bottom, as shown at 23, to permit the circulation of the air through the sides and bottom of the basket.

By placing the fan beneath the work in the manner illustrated in Fig. 1, the normal current of air produced by convection through the heaters is supplemented, the fan operating to cause the air to be forced laterally. The air which is forced laterally by the fan is heated by the heaters and rises and the current of air carries the air inwardly and downwardly to the work supported in the basket. The heated air passes downwardly through the basket and is again acted on by the fan and thus a continuous circulation is maintained. It has been demonstrated that a fan of the paddle type above described materially increases the efficiency of the furnace and that the time required for heat treatment is cut down to a very considerable extent over the time required in the ordinary furnace or in the furnace having a propellor type fan

for supplementing the circulation of the air therein.

The use of the paddle type of fan in a furnace or oven is not limited to the particular 5 mounting shown in Figs. 1 and 2 but has been found to be very beneficial in a furnace structure such as that shown in Fig. 3. It is not always practical to support the work to be treated in a basket which is spaced from the 10 floor of the furnace and to mount the fan between the basket and the floor. For example, in high temperature ovens or furnaces, such as those used for carbonizing steel, it is impractical to use metal supports 15 for the work and the work is, therefore, usually placed on the floor of the furnace. Furthermore, in large ovens or furnaces where mechanical loading is employed, the loading mechanism ordinarily delivers the 20 work on the floor of the oven or furnace.

Under conditions such as those above described, the fan may be mounted in the manner shown in Fig. 3, in which the motor 20 is mounted on the cover or lid of the oven 25 and the fan is disposed on the opposite side or inside of the cover. Instead of mounting the fan on the cover or above the floor of the furnace, it can be mounted on one of the vertical walls. It has been found that the paddle 30 type of fan, whether mounted in the manner shown in Figs. 1 or 3, or on one of the vertical walls of the furnace, materially increases the circulation of the air in the furnace and results in a greatly increased efficiency in the 35 operation of the furnace.

Although certain specific embodiments of the invention have been particularly shown and described, it will be understood that the invention is capable of modification and that 40 changes in the construction and in the arrangement of the various cooperating parts may be made without departing from the spirit or scope of the invention, as expressed in the following claims.

45 What I claim is:

1. A furnace comprising a heating chamber, heaters therein, a work support, and an air circulating fan disposed below said work support, said fan having radial plane blades 50 arranged to direct the air normal to the walls of the furnace.

2. A furnace comprising a heating chamber, heaters therein, a work support, and an air circulating fan disposed below said work support, said fan having a vertical drive shaft and blades disposed radially of said shaft and in vertical planes.

3. A furnace of the character specified comprising a heating chamber, heating means 60 therein, and a paddle type fan in said chamber having blades vertically disposed relative to said chamber, for directing air normal to the walls of the furnace.

65 4. A furnace of the character specified comprising a heating chamber, heating means

therein, and a paddle type fan in said chamber for circulating air therein, the axis of rotation of the fan being vertically disposed, for directing the air normal to the walls of the furnace.

5. A furnace comprising a heating chamber, heaters arranged adjacent the walls of the chamber, and an air circulating fan arranged with its axis adjacent the center of the chamber and having fan blades extending radially of said axis and in planes intersecting in a line coinciding with said axis for directing the air normal to the walls of the furnace.
